Primary Examiner — Robin V Webster(74) *Attorney, Agent, or Firm* — Michael J. Feigin, Esq.; Feigin and Fridman(57) **CLAIM**

The ornamental design for a distillation chamber, as shown and described.

DESCRIPTION

FIG. 1 shows a top and side perspective view of a distillation chamber.

FIG. 2 shows a bottom and reverse side perspective view thereof.

FIG. 3 shows a side view thereof the reverse side being a mirror image thereof.

FIG. 4 shows a front view thereof.

FIG. 5 shows a rear view thereof.

FIG. 6 shows a top plan view thereof.

FIG. 7 shows a bottom plan view thereof; and,

FIG. 8 is a cross-sectional view thereof, taken along line 8-8 of FIG. 4.

The portions within the area of the broken lines are included for the purpose of illustrating variable length of the distillation chamber and form no part of the claimed design.

1 Claim, 6 Drawing Sheets(56)
